Primary Examiner — W. A. Teddy Falloway(74) *Attorney, Agent, or Firm* — D'Ambrosio & Menon, PLLC; Usha Menon(57) **CLAIM**

The ornamental design for an index zipper bag, as shown and described.

DESCRIPTION

FIG. 1 is a front view of an index zipper bag, showing our new design

FIG. 2 is a back view of the design of FIG. 1;

FIG. 3 is a left side view of the design of FIG. 1;

FIG. 4 is a right side view of the design of FIG. 1;

FIG. 5 is a top view of the design of FIG. 1;

FIG. 6 is a bottom view of the design of FIG. 1;

FIG. 7 is a perspective view of the design of FIG. 1;

FIG. 8 is a front view of a mirror image of the index zipper bag of FIG. 1, according to another embodiment, showing our new design;

FIG. 9 is a back view of the design of FIG. 8;

FIG. 10 is a left side view of the design of FIG. 8;

FIG. 11 is a right side view of the design of FIG. 8;

FIG. 12 is a top view of the design of FIG. 8;

FIG. 13 is a bottom view of the design of FIG. 8; and,

FIG. 14 is a perspective view of the design of FIG. 8.

The contour lines shown in the drawings represent the three-dimensional character and contour of the article, and are not intended to illustrate material, surface ornamentation or surface decoration.
